attorney.

UNITED STATES PATENT OFFICE.

RUDOLF EICKEMEYER, OF YONKERS, NEW YORK.

FULLING-MILL.

SPECIFICATION forming part of Letters Patent No. 289,901, dated December 11, 1883.

Application filed October 12, 1883. (No model.)

to all whom it may concern: Be it known that I, RUDOLF EICKEMEYER, of Yonkers, in the county of Westchester and State of New York, have invented certain new and useful Improvements in Fulling-Mills; and I do hereby declare that the following specification, taken in connection with the drawings furnished and forming a part thereof, is a clear, true, and complete description of the several features of my invention.

My said improvements are applicable to that general class of fulling-mills which embody a beater or fulling-stock, whether it be vibrated to and fro, as shown and described in the Letters Patent of M. Chase, No. 4,361, dated January 20, 1846, or lifted and dropped, like a hammer, as illustrated in the Letters Patent of Angelo Cattaneo, March 3, 1868, No. 75,122, and also in my prior Letters Patent Nos. 144,841 and 195,810, respectively dated November 25, 1873, and October 2, 1877, and it is immaterial what mechanism be employed for operating the beater, although I prefer that shown and claimed in my said Letters Patent No. 195,810, and also shown in the Letters Patent of W. C. Waring, No. 248,537, dated October 18, 1881.

While generally applicable as described, my said improvements relate specially to that particular class of beater or fulling-stock mills in which is employed, as the front of the fulling-bed, a hinged apron, as illustrated in said Letters Patent of Chase and Cattaneo, in my own Letters Patent No. 144,841, and also in the aforesaid Letters Patent of Waring, No. 248,537. In said Letters Patent of Chase the hinged apron is shown as coupled by a link to the beater-helve, and by said Cattaneo the hinged apron was shown to be coupled by a rod or link and an eccentric to a shaft driven by a belt from the main shaft of the mill, and in said Letters Patent of Waring the hinged apron is coupled to the beater-lifting mechanism, so that in all cases said aprons are vibrated during the movements of the beaters co-operating therewith. The hinged apron described in my aforesaid Letters Patent No. 144,841 is not automatically vibrated, but it is provided with means whereby it may be, by hand, readily moved inward and outward, and also with means whereby it may be fixedly set

or adjusted with reference to the working-face of the beater, and thereby vary the capacity of the fulling-bed and correspondingly change its form; but the hinged aprons, as shown and described by said Chase and Cattaneo, were limited to a certain range of movement, so that the internal capacities of their fulling-beds were unvariable. The fulling-mill described by Waring in his said Letters Patent has a vibrating apron and mechanism for connecting it with the beater-lifting cam-shaft, which enables the throw of said apron to be varied; but said connecting mechanism is so organized that its adjustment can only be effected while the mill is at rest; and therefore in practical use said mills are once adjusted for working on a given number of hats at a time, and, when in service, in each case as a charge of goods decreases in bulk, incident to felting, pieces of felt are successively introduced into the bed, for so occupying the space therein that the goods may be further compressed and tumbled, and thereby continue the felting operation to the desired extent.

With this reference to the state of the art in fulling-mills of the class referred to, the nature of my improvements should be readily understood, from the fact that my improved beater-mill differs from all others known to me, in that while it is at work the vibrating apron can be so adjusted as to progressively decrease (or, if desired, increase) the internal capacity of the fulling-bed, and to thereby so change the form of the bed as to cause the beater to variably operate upon the goods within the bed, and this I deem to be a novel feature of considerable practicable value.

To particularly describe my invention, I will refer to the accompanying drawings, in which Figure 1 represents partially in side view and in vertical section so much of a beater fulling-mill as is deemed necessary for illustrating the application thereto of my improvements. Figs. 2, 3, and 4 represent in side views the hinged apron and its vibrating and adjusting mechanism in various positions, as will be hereinafter described. Figs. 5 and 6 are respectively detached front and top views of the vibrating and adjusting mechanism.

As here shown, the frame A, fulling-bed B,

hinged apron C, beater D, and its helve E are all substantially as heretofore. No mechanism for operating the beater is here shown, because, as hereinbefore indicated, it in no manner pertains to my present invention. The vibratory movement of the hinged apron C is provided for by means of a hinged connection with the beater-helve. A rock-shaft, *a*, is mounted crosswise in the frame A at the front of the mill, and it carries loosely a pair of levers or arms, *b*, each of which extends in opposite directions from said shaft, so as to rock thereon. These arms *b* are connected at their inner ends by a rod, *b'*, to which the lower end of a link, *c*, is pivoted, and the upper end of said link is pivoted to the outer end of a bracket-arm, *d*, projecting from the under side of the beater-helve E, so that as the beater is lifted and dropped the arms *b* are rocked upon said rock-shaft by the longitudinal reciprocation of said link *c*. Tightly mounted on said rock-shaft is a pair of counterpart bell-crank levers, *e*, pivotally connected at their inner ends by links *f* to the rear or back of the hinged apron C, near its top. These bell-crank levers *e* are connected to the loosely-mounted rocking levers or arms *b* by means of the adjusting hand-screw *g*. The pair of bell-crank levers *e* are coupled at their outer ends by a cylindrical block or bar, *h*, which is swiveled or axially mounted in said levers, and it is diametrically bored centrally, to afford a loose bearing or yoke for the neck of the hand-screw *g*, between its crank and a collar-nut, *h'*, on the threaded portion of the screw. The two rocking levers or arms *b* are similarly connected at their outer ends by a similar axially-mounted block or bar, *b'*, similarly bored, but tapped to serve as a swivel-nut for receiving the said screw, so that when the latter is turned to and fro the relative positions of the bell-crank levers and the arms *b* will be axially changed, and correspondingly advance or retire the upper end of the hinged apron toward or from the working-face of the beater. It is obviously immaterial which of the two pairs of levers is loose on the rock-shaft, or whether both are loose thereon, so far as relates to the adjusting action of the screw. When the beater is lifted, it will be seen that the upper end of the link *c* will be moved inwardly in the arc of a circle of which the helve-pivot *i* is the center, and that the apron C will be thereby moved forwardly until the upper end of said link is in line with the helve-pivot *i* and the pivot at *b'* at the lower end of said link, and that as soon as the beater begins its falling movement the apron commences to retire, but concludes its movement at the moment the beater has completed its drop and is in full compressing contact with the goods within the bed.

In Fig. 1 the apron C is shown in the position which affords the greatest internal capacity of the fulling-bed and with the beater in its lowest position, while in Fig. 2, with the same adjustment by the screw, the apron is

shown with its top in its most advanced position, as when the beater has been fully lifted. In Figs. 3 and 4 the adjusting-screw *g* is so turned as to separate the outer ends of the levers *b* and *e* to their fullest extent, which throws the upper end of the apron forward into a position which affords a minimum capacity of the fulling-bed and radically changes the form of said bed. In Fig. 3 the apron C is shown as when the beater is in its lowest position, and in Fig. 4 as when the beater has been fully elevated, and in all the possible variations of adjustment the range of vibratory movement by the apron will be substantially uniform. It will be readily seen that the screw *g* serves as a means for practically extending and for reducing the distance between the outer end of the link *c* and the point of connection between the apron C and links *f*, and that the arms *b* and levers *e* serve as coupling media between the links *c* and *f*, and therefore it will be obvious that approximately desirable results will accrue if the link *c* be constructed in two equal parts or lengths oppositely threaded, and connected at their coincident ends by a sleeve having internal right and left hand threads, and a hand-wheel for readily lengthening and shortening the link, in lieu of the screw *g*; and with that construction the levers *b* and *e* may both be connected to the rock-shaft, or they may be in one piece, or said levers may be dispensed with, in which case the link *c* will be of proper length to be connected directly with the apron C; and it is to be understood that I deem such variations in construction and arrangement of the mechanism for connecting the apron C with any movable part of the mill as within the main portion of my invention, provided the hand-screw or its equivalent be employed for varying the position of said apron, as described. As a rule, I prefer to rely upon connections between the beater-helve and apron; but the latter may, without departure from my invention, receive its motion from a cam-shaft for lifting the beaters, as described in my aforesaid Letters Patent No. 195,810, and also as shown in said Letters Patent of Waring, No. 248,537; or said apron may be vibrated, as shown in the aforesaid Letters Patent of Cataneo, from a belt-driven shaft connected to the apron by an eccentric and rod, because the latter can be readily lengthened or shortened by a sleeve-nut having a hand-wheel, as hereinbefore indicated, and thereby while the mill is in motion enable the desired variation in the working relations of the apron and the beater.

Fulling-mills embodying my present improvements are of special value in fulling or sizing felt-hat bodies; but it is obvious that they can be profitably employed for fulling other classes of goods.

Having thus described my invention, I claim as new and desire to secure by Letters Patent—

1. The combination, substantially as hereinbefore described, of the fulling-mill beater;

the vibrating fulling-bed apron, and means, substantially as described, for adjusting the apron with reference to the working-face of the beater while the mill is in motion and 5 during the felting operation, as set forth.

2. The combination, in a beater fulling-mill, of the link longitudinally reciprocated by connection with any movable part of the mill, the hinged apron coupled to said link, and an adjusting hand-screw for practically elongating and shortening said link, substantially as described, whereby the apron can be made to vibrate in various positions while the mill is in motion and during the felting operation, as 15 set forth.

3. The combination of the longitudinally reciprocating link, the vibrating hinged fulling-bed apron, the levers, the links *f* for connecting said reciprocating link with said apron, 20 and the hand-screw connected to said levers for varying their positions, and thereby varying the position of the apron during its vibration, substantially as described.

4. The combination, with the beater and its helve, of a link pivoted to the helve, a vibrating fulling-bed apron connected with said link, and an adjusting-screw for practically varying the length of the link, substantially as described. 25

5. The combination, with the beater-helve, 30 the vibrating hinged fulling-bed apron, and the link pivotally connected to said helve, of the rock-shaft, the levers and arms thereon, respectively connected pivotally to said link and apron, and the adjusting hand-screw for varying the relative positions of said levers and arms, and thereby practically elongating the link and varying the position in which the hinged apron vibrates, substantially as described. 35
